UNITED STATES PATENT OFFICE

ROBERT DELTHEIL, OF TOULOUSE, FRANCE

LIQUID CONTAINER

Application filed August 16, 1927, Serial No. 213,232, and in Belgium September 2, 1926.

The present invention relates to liquid containers and, more particularly, to those to be used for containing vaporizable liquids such as perfumes, insecticides and the like.

5 One of the objects of the invention is to provide a form of container which may be kept sealed and which gradually liberates the volatile liquid contained therein.

A further object is to provide a container 10 and means for controlling the evaporation of liquid therefrom.

Additional objects will appear in the course of the detailed description now to be given with references to the accompanying drawings, in which:—

Fig. 1 is an elevation of one form of container constructed in accordance with the invention;

Fig. 2 shows the container represented in Fig. 1, in section;

Fig. 3 illustrates a second form of container;

Fig. 4 is a section of the container shown in Fig. 3;

25 Fig. 5 represents a third form of container;

Fig. 6 is a section through the container shown in Fig. 5;

Fig. 7 is a section through a fourth form of the invention adapted for pocket use;

30 Fig. 8 is a section representing a variant of the form of invention illustrated in Figs. 1 and 2;

Fig. 9 shows, in perspective, a container arranged so as to distribute perfume to cigarettes mounted in a common case therewith; 35 and

Fig. 10 is a section through a form of container adapted to be carried in a pocket.

Referring to the Figures 1 to 4 and 8 of the drawing, there is shown a bottle or container *a* having a neck portion *b* fitted with a stopper *c*. Container *a* is provided with one or more capillary orifices *f* which communicate with a porous plate *d* mounted outside of (Figs. 1 to 4), or in a recess formed in (Fig. 5) the walls of container *a*. The porous material may be felt, pumice stone, unglazed porcelain or any equivalent permeable material. In actual practice, unglazed porcelain is found to give the best result. Porous ele-

ment *d* may be left bare, as in the modification shown in Figs. 1 and 2, or covered with a perforated plate *h* serving to simultaneously diminish the evaporation and to protect element *d* against breakage, as in the modification represented in Figs. 3 and 4. If it be desired to provide means for regulating the rate of evaporation plate *h* may be covered by a second perforated plate *i* (Fig. 8). By sliding plate *i* relative to plate *h* any desired portion of element *d* may be exposed for evaporation.

The modification shown in Figs. 5 and 6 differs from those shown in Figs. 1 to 4 only in the absence of capillary *f*. In this form 65 of the invention, porous element *d* forms part of the container wall and communicates directly with the container contents. The device shown in Fig. 7 is a variant of that shown in Figs. 5 and 6, with porous element *d* forming part of the body of the stopper.

Fig. 9 shows how the container may be mounted with an article to be perfumed *k*—cigarettes—in a common receptacle *j*.

The form of device shown in Fig. 10 is intended for pocket use. The neck portion *b* of container *a* is here fitted with a stopper *m* provided with capillary *f*. The porous element *d* is mounted on stopper *m* and is protected by perforated screen *h*. This form 70 of device functions in the same way as those already described.

It is important that orifices *f*, shown in certain of the figures, be true capillaries so that the flow of liquid to the porous element 85 be not excessive. When the container is to be used to evaporate a disinfectant and a rapid rate of evaporation is desired, the area of plate *d* should be increased and the number of capillaries increased in proportion to the 90 increased evaporating surface employed.

What I claim is:—

1. In a device for diffusing volatile liquids, a container having a capillary orifice formed in a wall thereof, and a porous evaporating 95 element mounted on said container in communication with said capillary orifice.

2. In a device for diffusing volatile liquids, a container having a capillary orifice formed in a wall thereof, a porous evaporating ele- 100

ment mounted on said container in communication with said capillary orifice, and means for diminishing the evaporation from said porous element.

5. In a device for diffusing volatile liquids, a container having a capillary orifice formed in a wall thereof, a porous evaporating element mounted on said container in communication with said capillary orifice, and a perforated screen covering at least part of said porous element.

10. 4. In a device for diffusing volatile liquids, a non-porous container having a capillary orifice in a wall thereof, and a porous element obstructing said orifice.

15. 5. In combination, a container having a capillary opening in a wall thereof, and a rigid porous element obstructing said opening and adapted to remove a liquid inside the container by capillary attraction.

20. 6. In combination, a container having a capillary opening in a wall thereof, a porous element obstructing said opening, and means for varying the evaporation of liquid from said porous element.

25. In testimony whereof I have hereunto set my hand.

ROBERT DELTHEIL.
